UNITED STATES PATENT OFFICE.

FLEMING H. PECK, OF SEATTLE, WASHINGTON.

FORM FOR MOLDING CONCRETE WALLS.

Application filed July 21, 1922. Serial No. 576,429.

To all whom it may concern:

Be it known that I, FLEMING H. PECK, a citizen of the United States of America, and resident of the city of Seattle, in the 5 county of King and State of Washington, have invented certain new and useful Improvements in Forms for Molding Concrete Walls, of which the following is a specification.

10 My invention relates to the construction of forms used in molding concrete structures and consists of certain parts constructed in such a way that they may be used as the frame work or supporting members 15 for the boards or like members which are used to shape the outer surface of the concrete.

The object of my invention is to provide the material used for the construction of 20 these forms, in such shape that it is readily adapted to all the varying sizes and forms in which it is ordinarily desired to mold concrete for structural purposes and to have this material such that it may be quickly 25 put in place and also quickly disassembled or taken down.

My invention consists of the features of construction and novel combinations of parts which I will hereinafter describe and 30 then particularly point out in the claims terminating this specification.

In the accompanying drawings I have shown my invention in a construction which is that now most preferred by me.

35 Figure 1 is a top or plan view of my invention as applied to the forming of a corner in a foundation wall.

Figure 2 is a side view or elevation of the same parts.

40 Figure 3 is a sectional elevation showing enough construction to indicate the manner of applying this in the molding of ordinary wall.

Figure 4 shows, in perspective, the manner of placing the mold for two walls joining at the corner.

Figure 5 is a sectional elevation showing slightly modified construction of one of the parts.

50 In the formation of concrete walls the cost of constructing the molds mounts often to a very considerable item. It is a purpose of this invention to provide a construction of certain parts, such that they may be used to quickly assemble these molds and such that after the concrete wall has been formed

and set, the molds may be quickly taken down and without destroying the parts thereof, so that these may be again used at other points. The chief and novel features lie in the construction of the posts which are employed for holding the boards used in their proper place and the manner of supporting these in proper position and securing the board thereto.

For the posts to which the boards are to be secured I employ rolled metal sections, these being cut of a suitable length. These posts may be made of different sections, but the section which I most prefer to use is 70 the angle bar. These bars 1 have a series of holes, 10, distributed at short distances along the length of both flanges thereof and preferably well toward the outer edges of the flanges as thus it will be easy to drive 75 nails through these holes. These holes are provided in both flanges, so that either flange of the angle bar may be used against which to secure the boards. The boards 2 are placed against the faces of post 1, and 80 small nails inserted in the holes 10 and driven into the wood. Preferably these nails should be of such a length that they will not pierce the opposite, or inner face 85 of the boards.

The ends of the bars 1 are provided with notches 11, which are preferably made at the junction of the two flanges. These notches may be V-shaped or square at the bottom as desired. The ends of the bars 90 may be secured together by using a rod, as 3, which has its ends bent laterally to form offset sections or hooks 31 which hook over the outside of the bars and which prevent 95 their separating beyond a certain distance. These connecting rods 3 may be straight, except for a single bend 30 at the ends, or they may be made as shown in Figure 5, wherein they are bent to form a U-shaped end 31, the two sides of which are shaped so as to snugly fit over the flange of the angle bar. In this case these rods act as 100 spacers to prevent the bars 1 from being brought together and also as tie rods to prevent separation. The spacing apart of the two walls of the mold may be secured by the insertion of wood blocks which would be removed before they become buried in the concrete, or in any other suitable manner.

Where the length of the posts 1 which are being employed is so great that supporting

tie rods are needed between their ends, this may be secured by using wires, as 4, which connect opposite posts and which may be left in the wall. These wires may be made 5 of such a size that they may be passed through the holes 10 in the flange, as is shown in Figure 3, or they may be passed entirely around the angle bars, as is shown 10 in Figures 1 and 2. These wires may be passed between adjacent edges of two of the boards which form the walls. The ends of the wire may be twisted together and this joint may be made at any point desired, either within the space to be occupied by 15 the wall or outside of the forms. When it is desired to take down the forms, these wires will be cut and the ends which project from the finished wall will be cut off flush with the wall, by the use of wire cutters.

20 I prefer to provide the ends of the bars 1 with a hole 5 of such size that a rod 50 of material size may be passed therethrough. Such a rod may be employed for connecting a number of posts 1 and thus, at times, help 25 to keep the posts together and to assist in the construction of the molds. The rods 5 may, whenever desired, be provided with spacers which will hold the posts 1 definite distances apart.

30 After the concrete has been poured in a mold and has been set so that it is desired to remove the molds, the tie rods 3 are readily removed. The tie rods 3 which connect the lower ends of the bars 1, must be left 35 in the wall, if they are used at this point. The tie wires 4 may also be cut. It is then an easy matter to pry the bars 1 free from the boards 2, as the nails used to secure the 40 bars through which the nails pass fit snugly around the nail and, in consequence, the material forming the molds need not be

broken in knocking down the molds. It may therefore be substantially all used again 45 for forming molds.

What I claim as my invention is:

1. A post for use in forming molds for concrete walls consisting of an angle bar having nail holes distributed along its flanges and notches opening at their ends 50 and adapted for the reception of tie rods.

2. A form for use in molding concrete walls comprising a series of angle bars having nail receiving holes spaced along their flanges, and boards secured by nails driven 55 through said holes, and tie rods having hooked ends adapted to engage posts at opposite sides of the wall to prevent their separation.

3. A form for use in molding concrete 60 walls comprising a series of angle bars having nail receiving holes spaced along their flanges, and notches in their ends, tie rods having hooked ends adapted to enter said notches, and boards secured by nails driven 65 through said holes.

4. A post for use in making forms for concrete walls comprising an angle bar having nail-receiving holes spaced along its flanges and a notch opening at its end and 70 including the bases of each flange and adapted for the reception of tie rods.

5. A form construction for concrete walls comprising posts composed of angle bars provided with nail-receiving holes in their flanges and a notch in each end located at the point where the two flanges join, and tie rods having laterally bent ends and adapted 75 to enter said notches and to hold together opposite sides of the wall. 80

Signed at Seattle, King County, Washington this 15th day of July, 1922.

FLEMING H. PECK.
